UNITED STATES PATENT OFFICE.

OTTO W. NIEDOMANSKI, OF WASHINGTON, DISTRICT OF COLUMBIA.

PENCIL-SHARPENER.

1,089,946.

Specification of Letters Patent. Patented Mar. 10, 1914.

Application filed July 2, 1913. Serial No. 776,963.

To all whom it may concern:

Be it known that I, Otto W. Niedomanski, a citizen of the United States, and a resident of Washington, in the District of Columbia, have made certain new and useful Improvements in Pencil-Sharpener, of which the following is a specification.

My invention relates to pencil sharpeners of the type suitable to be carried in the pocket and easily handled, my more particular purpose being to increase the efficiency of the sharpener while promoting the simplicity of the construction thereof.

Reference is made to the accompanying drawing forming a part of this specification, and in which like letters indicate like parts.

Figure 1 is a perspective showing my improved pencil sharpener ready for use. Fig. 2 is a vertical section on the line 2-2 of Fig. 1, looking in the direction of the arrow. Fig. 3 is a section on the line 3-3 of Fig. 2, looking in the direction of the arrow. Fig. 4 is a fragmentary detail of the cutting blade of the pencil sharpener.

25 A body member is shown at 5, and in this instance is made of wood, though it may as well be composed of other material. This body member is provided with a groove 6 extending the entire length of the body member and having a substantially flat bottom. The body member 5 is provided with a compartment 7, this compartment being bounded in part by an inner facing 8 and a step 9, and also by an obliquely disposed inner facing 10.

The body member 5 is further provided with a slot 11 partially bounding the face 10, this slot serving as a slideway. The slot 11 is provided with portions 12 which merge into opposite sides of the groove 6 and extend nearly flush with the outer upper surface of the body portion.

40 A cutting blade is shown at 13 and is provided with a slot 14. This cutting blade is fitted into the slideway 11 and may be adjusted relatively thereto in the general direction of the length of the blade. Extending through the slot 14 is a screw 15 provided with a head 16. By tightening the screw the blade 13 is held rigidly in position, but by loosening the screw the blade may be adjusted, the screw being tightened after each adjustment.

The blade 13 is provided with a straight, 55 sharp edge 17, and is further provided with a bevel 18, this bevel extending completely

across the groove 6, as will be understood from Fig. 3. The blade fits into the slot 13.

A plate 18^a is provided at one of its ends with a bevel 18^b and at its opposite end with a bent portion 18^c. The body member 5 is provided with grooves 18^d which merge into the upper portions 12 of slots 11, as may be understood from Figs. 2 and 3. The plate 18^a when in position as indicated in Figs. 1 and 2, extends nearly into engagement with the blade 13, and serves as a lining for the bottom of the groove 6. The top of the plate 18^a, according to Figs. 1 and 2, is flush with a surface 18^e of the wooden or body member, this surface being so located, however, that the bevel 18 of the blade extends between it and the plate 18^a. An opening 18^f is left between the step 9 and the straight edge 17 of the blade.

75 A slide 19 is provided with a bent portion 20, the latter serving as a limiting stop. This slide is fitted into a slot 21 with which the body member 5 is provided.

When the blade 13 is in position, as indicated in Fig. 2, there is a little space 22 between the sharp edge of the blade at the middle portion thereof, and the shoulder 9.

The operation of my device is as follows: The parts being assembled as above described, the blade 13 is adjusted and the slide 19 is fitted into position as indicated in Fig. 2. The operator now holds the body portion 5 and extends a pencil into the groove 6, the pencil inclined to any suitable angle 90 relatively to the adjacent surface of the plate 18^a. By alternately pulling the pencil backward and advancing it past the exposed bevel 18 of the cutting blade, the operator cuts away the small shavings from the pencil 95 thus sharpening the pencil. The rubbish or shavings detached from the pencil pass through the space 22 and into the compartment 7.

I find that the effectiveness of the device 100 is greatly improved by use of the plate 18^a, this plate being of metal admits of it being made smooth and accurate and its capacity to guide the pencil further is thus greatly increased. Whenever the operator desires 105 to throw out this material he opens slide 19 for the purpose.

I claim:

A pencil sharpener comprising a body having central longitudinal grooves along 110 relatively opposite sides thereof and provided with a transverse intermediate com-

partment communicating with said grooves, said body also having longitudinally extending slots along opposite sides, and adjacent the bases of said grooves, a plate mounted 5 in the compartment and having a sharpened edge projecting slightly beyond the base of one of the grooves, and plates slidably and removably engaging the said slots within the grooves and having angular ends forming 10 handles and abutting one end of the body, one of said plates being adapted to extend

adjacent to the sharpened edge of the plate and to form a base for the respective groove upon which a pencil to be sharpened may be moved, and the other plate forming a closure 15 at its respective end of the compartment, all for the purpose described.

OTTO W. NIEDOMANSKI.
